UNITED STATES PATENT OFFICE.

GEORGE W. LEWIS, OF GRINNELL, IOWA, ASSIGNOR TO GRINNELL WASHING MACHINE COMPANY, OF GRINNELL, IOWA, A CORPORATION.

CLOTHES WRINGER.

1,411,443.

Specification of Letters Patent.

Patented Apr. 4, 1922.

Application filed May 11, 1920. Serial No. 380,656.

To all whom it may concern:

Be it known that I, GEORGE W. LEWIS, a citizen of the United States, and resident of Grinnell, in the county of Poweshiek and 5 State of Iowa, have invented a certain new and useful Clothes Wringer, of which the following is a specification.

My invention relates to that class of clothes wringers intended for use in connection with so-called power washing machines, and in which the wringer is operated by power from an electric motor or the like, instead of by hand.

The objects of my invention are:

15 To provide a wringer of this class, of simple, durable and inexpensive construction and of neat and attractive appearance, and so arranged that in the event that the operator's hand should become caught between the wringer roll, or clothes should become caught or entangled around one of the wringer rolls, the operator may quickly and easily, by touching a lever, instantly separate the wringer rolls and remove all 20 pressure therefrom, so that the operator's hand or the entangled clothes may be quickly disengaged without damage or injury.

More specifically, in this connection, it is 30 my object to provide a device of this class in which the separation thus effected shall be along a central line between the two wringer rolls, so that all of the spring tension device that is ordinarily applied to 35 the upper roll will be carried by the upper half of the frame when this separation is made, and so that when the operator's hand, or the clothes, have been disengaged from the wringer rolls, the device may again be 40 put in condition for operation by simply pressing downwardly upon the upper half of the frame and moving it to its normal position for use, and without the necessity of readjusting the tension screws of the 45 spring tension device.

A further object is to provide an improved means for adjusting the tension of the upper wringer roll, especially designed for use in connection with a wringer that 50 is capable of separation on a central line between the rolls.

Still a further object is to provide an improved releasing device of simple, durable and inexpensive construction, so arranged 55 that it may be released quickly and easily by moving the lever in any direction, so that

the operator need not remember which particular direction the lever should be moved in in order to separate the rolls.

Still a further object is to provide an improved drain board for a wringer of this class, capable of being quickly and easily reversed in its position, to drain the water in either direction from the wringer roll.

Still a further object is to provide an improved frame for a wringer of this class, which forms a clothes guide and protector for the wringer rolls, and whereby the danger of having the operator's hand become caught in the wringer rolls is reduced to a minimum.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a side elevation of a wringer embodying my invention, partly in section.

Figure 2 shows a sectional view on the line 2—2 of Figure 1.

Figure 3 shows a sectional view on the line 3—3 of Figure 1, the drain board being shown by dotted lines in a reversed position.

Figure 4 shows an enlarged, detail, sectional view, illustrating the spring latch device.

Figure 5 shows an enlarged, detail, sectional view through the transverse central portion of the upper part of the wringer, to illustrate the arrangement of the tension spring and bearings for the upper wringer rolls.

Figure 6 shows an enlarged, detail sectional view of the drain board.

Figure 7 shows an enlarged, detail sectional view on the line 7—7 of Figure 6; and

Figure 8 shows a reduced, side elevation of the wringer, with the upper section thereof elevated above the lower section.

Referring to the accompanying drawings, I have used the reference numeral 10 to indicate a bracket upon which the entire wringer is supported. This bracket may be secured to a stationary or movable support, as desired.

Formed on or fixed to this bracket is the lower wringer roll section of the frame,

which is preferably cast complete in one piece with the bracket. This comprises a body portion 11, substantially semi-circular in cross-section, as shown in Figure 3, and is provided with downwardly extending lugs 12 at its end portions for the purpose of supporting the drain board, as will herein-after appear. The opposite sides of this lower body portion are cut away at 13 so as to expose through the opening thus formed, only the upper half of the lower wringer roll, and to enclose the ends of the wringer roll so that the operator's hand or clothing cannot enter beneath the lower roll or between the ends of the lower roll and the ends of the frame, and so that the upper part of this body portion will serve as a clothes guide upon which the operator may rest her fingers when inserting clothes between the wringer rolls.

Formed on the interior of the lower body portion 11, near the ends thereof, are the parallel vertical ribs 14, designed to receive between them and to serve as guides for, the bearing frames 15 for the lower wringer roll. These bearing frames are of the ordinary construction, and are not herein specifically shown or described. They are, however, shaped to be received between and supported by said ribs 14.

The lower wringer roll is indicated by the numeral 16, and its shaft by the numeral 17. It is arranged to be driven by power in the ordinary manner, not here shown.

The upper frame member is indicated generally by the reference numeral 18, and is like the lower one except that it is inverted. It is connected at one end by the hinged member 19 to the bracket 10. It is provided on its interior, at each end, with the vertical, parallel ribs 20, between which the bearing devices 21 of the upper wringer roll may move vertically to a limited extent.

The upper wringer roll is indicated by the numeral 22, and its shaft by the numeral 23.

The tensioning device for the wringer comprises a leaf spring of arched form, indicated by the numeral 24. Its central portion rests against the top of the upper frame member between the lugs 25 which hold it in line. Its ends extend outwardly and downwardly, and rest upon the top of the wringer roll bearing frame 21, to thereby normally exert a yielding pressure downwardly upon the bearings of the upper wringer roll.

For adjusting the tension of the upper roll, I have provided at each side of the upper frame member a screw 26 seated in the yoke 27 which is formed on or fixed to the upper bearing frame member 21, as shown in Figure 2. When said screw is turned to raise the yoke, the tension of the upper wringer roll is reduced, and when it

is moved in the opposite direction the tension upon the upper wringer roll is increased. By this arrangement it is obvious that when the upper frame member is separated from the lower one, as shown in Figure 8, the tension of the spring and the position of the upper roll and its bearing are not changed relative to the frame, so that when the wringer is thus separated it can be readily and easily returned to its normal position without any manipulation of the spring adjusting screws.

I have provided a releasing device of simple and inexpensive construction, as follows:

Mounted in suitable bearings on one side of the frame member is a shaft 28 having a handle 29 extended upwardly and outwardly beyond the end of the wringer frame. On the part of this shaft that extends inside of the wringer frame is a flat latch releasing member 30, and mounted in suitable bearings adjacent thereto is a latch 31 having a hook at its upper end, designed to normally engage and coact with a lug 32 on the upper wringer frame member. A spring 33 is provided for yieldingly holding the latch 31 in position in engagement with its lug 32, as clearly shown in the enlarged sectional view in Figure 4.

By this arrangement it is obvious that when the handle 29 of the shaft 28 is moved in either direction, the latch 30 will be disengaged from its lug 32, and the upper frame member will immediately spring upwardly by reason of the tension on the upper roller, and the device will thus be separated to the position shown in Figure 8. Then when the operator's hand is removed from the handle 29, the upper wringer frame member may be moved downwardly and the spring 33 will cause the latch to first move the handle 29 to a neutral position, and then it will engage with its coacting lug 32 and lock the upper frame member.

My improved drain board device comprises a body portion 34 having upwardly extending lugs 35 at its ends, which are connected by the pivot points 36 to the lugs 12, so that this drain board may be tilted to either of the positions shown in Figure 3.

For holding the drain board in either of these positions shown in Figure 3, I have provided in the bottom portion of the frame member 11 a spring actuated bolt 37, designed to engage a rib 38 formed on an extension 39 at one side of the drain board member above its pivot point, as clearly shown in Figures 6 and 7. By this arrangement it is obvious that one edge of the drain board may be grasped by the operator's hand, and it may be moved to the desired position, and during this movement it will compress the spring of the bolt 37 until the rib has passed the bolt, and then the spring

will again extend the bolt and hold it locked in either of its said positions.

In Figure 8 of the drawings I have shown an electric lamp 40, mounted in a socket 5 formed in the upper frame member. This is a great convenience in connection with a machine of this kind, and avoids accidents due to insufficient lighting around the wringer when it is in use.

10 In practical use, and assuming that the wringer frame is in its closed position, the wringer is operated in the ordinary manner by power, and the tension of the upper wringer roll may be readily and easily 15 adjusted by the adjusting screws 26.

If at any time an article should become caught or entangled in the wringer rolls, the operator may, by merely touching the handle 29, and moving it in either direction, cause 20 the upper wringer roll and the upper part of the frame to instantly separate from the lower part, which instantly relieves the tension and permits the withdrawal of the article. When this is done the upper wringer 25 roll, its bearings and the tension spring are all retained in their normal position, and then the device may be pressed downwardly to closed position, and latched, without the necessity of readjusting the spring tension 30 device.

I claim as my invention:

1. A wringer comprising a lower and an upper frame member hinged together at one end, a releasable latch device for connecting 35 them at their free ends, a roll in each frame, sliding bearings for the upper roll, an adjustable spring tension device carried by the upper frame member and normally exerting a yielding pressure downwardly upon 40 the upper roll, and means for limiting the downward movement of the upper roll, for the purposes stated.

2. In a clothes wringer, the combination 45 of a frame divided along a substantially central horizontal line, the upper part being hinged to the lower part at one end, a wringer roll mounted in each part of the frame, a latch device for securing the free ends of the frame together, said latch device 50 comprising a latch hinged to one of the frame members, a lug on the other frame member to coact with the latch, a spring for the latch, a shaft mounted in the frame member adjacent to the latch and having a 55 flat surface designed to engage the latch, and when turned in either direction to move the latch away from the lug, and a handle connected with said shaft, said parts being so arranged that when the handle is moved 60 in either direction the latch will be released.

3. In a clothes wringer, the combination 65 of a frame divided along a substantially central horizontal line, the upper part being hinged to the lower part at one end, a wringer roll mounted in each part of the

frame, a latch device for securing the free ends of the frame together, a roller spring tension device mounted in the upper frame member and designed to press downwardly upon the upper roll, and means for limiting 70 the downward movement of the upper roll so that when the parts of the frame member are separated the wringer roll and the tension spring will remain in position.

4. In a clothes wringer, the combination 75 of a lower frame member substantially semi-circular in cross-section, an upper frame member hinged thereto at one end, and also substantially semi-circular and cross-section, 80 said frame members having at their opposite sides openings to permit the insertion of clothes between the wringer rolls, the margins of said openings being designed to serve as clothes guides for the operator, and the sides of said frame members adjacent to said 85 openings being shaped to cover the ends of the wringer rolls, the upper part of the upper roll and the lower part of the lower roll, and means for releasably securing the free ends of said frame members. 90

5. In a clothes wringer, the combination 95 of upper and lower frame members hinged together at one end, a roller mounted in the lower frame member, a roller in the upper frame member, bearing members for the 100 upper frame members, a yoke secured to each of said upper bearing members, adjusting screws mounted in the upper frame member, seated in said yokes, and a spring tension device connected with the upper frame member and also with the upper bearing members, for the purposes stated.

6. In a clothes wringer, the combination 105 of upper and lower frame members hinged together at one end, a roller mounted in the lower frame member, a roller in the upper frame member, bearing members in the upper frame members, a yoke secured to each of said upper bearing members, adjusting screws mounted in the upper frame 110 member, seated in said yokes, and a spring tension device connected with the upper frame member and also with the upper bearing members, said upper frame member being formed with vertical parallel guides in 115 which said roller bearing members are slidingly supported.

7. The combination with a wringer frame 120 having downwardly extending lugs thereon, of a reversible drain board pivotally supported in said downwardly extending lugs, one end of said drain board being provided with an upwardly extending projection formed with a vertical rib, and a spring actuated bolt mounted in the lower frame 125 member to coact with the rib for locking the drain board in different positions of its adjustment.

Des Moines, Iowa, April 20, 1920.

GEORGE W. LEWIS.
